UNITED STATES PATENT OFFICE.

AMBROSE RIDD, OF FARRELL, PENNSYLVANIA.

METHOD OF BLUING SHEETS AND PLATES.

1,192,347.

Specification of Letters Patent. Patented July 25, 1916.

Application filed March 27, 1916. Serial No. 86,927.

To all whom it may concern:

Be it known that I, AMBROSE RIDD, a citizen of the United States, and resident of Farrell, in the county of Mercer and State of Pennsylvania, have invented certain new and useful Improvements in Methods of Bluing Sheets and Plates, of which the following is a specification.

My invention relates to the manufacture 10 of blued sheets and plates of rolled ferrous metal.

One object of the invention is to provide a novel method of bluing such rolled sheets and plates wherein individual sheets or 15 plates are uniformly heated within a suitable furnace to the desired temperature and the individually heated sheets or plates are gradually withdrawn from the furnace and progressively cooled by exposure to the atmosphere in oxidizing the surfaces of the 20 plates to an equable blue color.

Another object of this invention is to provide an improved method of bluing rolled metal sheets and plates whereby overheating 25 of the edges of the sheets is avoided and prevented and the necessity of heating the sheets or plates in bulk or packs is overcome and made unnecessary, and wherein the sheets or plates are heated individually 30 and in a substantially continuous manner and the desired uniform color on the surfaces of the sheets is obtained.

Referring now to the drawings forming part of this specification, Figure 1 is a longitudinal, sectional side elevation showing a furnace of the muffle type made in accordance with my invention and adapted for use in carrying out the improved method forming part of this invention. Fig. 2 is a 40 sectional end elevation of the furnace shown in Fig. 1, the section being taken on the line II—II of Fig. 1. Fig. 3 is a sectional plan of a portion of the furnace shown in Figs. 1 and 2, showing the staggered arrangement 45 of the supporting rollers as arranged in accordance with my invention.

In the accompanying drawings, the numeral 2 designates the heating or combustion chamber of a gas fired furnace having 50 side walls 3, 3, and end walls 4, 4, with an arched roof 5 carried by the side walls.

The furnace is provided with a stack 2^a of any of the usual known constructions. Positioned within the furnace chamber 2 is a muffle 6 formed of metal or of tiles, bricks, 55 or such other refractory material as is found necessary or desirable. The muffle 6 has open ends forming an inlet opening 7 and outlet opening 8, connecting the interior of the muffle with the exterior of the furnace, 60 the ends of the muffle being built into and supported by the end walls of the furnace. Suitable transverse supports (not shown) may be provided at intervals in the length of the furnace chamber 2 to sustain the 65 muffle when its length makes such supports necessary or desirable.

Extending lengthwise on the bottom of the combustion chamber 2 are brick walls forming baffles 10, 10, and in the walls 4, 4, 70 at each end of the passage 11 between the walls 10, 10, is an opening 12^a for a gas burner 12 having supply pipes 14 and 15 and valves 16, 16^a, by which air or gas or a mixture of air and gas is admitted to the passage to regulate and control the temperature 75 to which the middle of the heating chamber 2 and muffle 6 is heated.

Located in the side walls 3 of the furnace at the bottom of the chamber 2 is a series of 80 openings 13^a for the gas burners 13 which are similar to the burners 12 and have gas pipes 14 and air pipes 15, are valves 16 and gas valves 16^a being provided on the burner pipes 12 and 13 to control the air and gas 85 supply in regulating the heating of the furnace chamber and muffle to obtain the desired uniform temperature within the muffle or bluing chamber 6.

Positioned within the muffle 6 on the bottom thereof is a series of transverse supports 17 for the series of idler rollers 18 in the muffle and on which the sheets or plates 19 are supported when being heated and in passing into and through the furnace 90 muffle 6. The rollers 18 are arranged in two converging rows, the pairs of rollers being at a distance apart which increases from one end to the other of the furnace, so that in plan the rollers 18 are in staggered relation, this construction causing the sheets or plates 19 to be supported upon changing 95 100

and successively different portions of the lower surface of the sheets and plates and thereby assisting in equably heating the sheets and plates to the desired temperature.

5 Extending lengthwise within the muffle 6 adjacent to each vertical side wall 20 thereof is a series of cooling tubes 21 through which a supply of cold or cool air is passed, the tubes 21 being located at the sides of the 10 muffle 6 to prevent overheating of the muffle at the side walls thereof, as would otherwise occur and in this way assist in securing the desired uniform temperature within the muffle 6.

15 Fastened so as to be adjustable on the supports 17 for the idler rollers 18 within the muffle chamber are vertically extending metal shields 22, 22, these shields being adjustable sidewise within the muffle to suit the 20 particular width of the sheets or plates being heated. The upper edge 23 of the shields 22 is inclined upwardly and inwardly to overlap the edges of the sheets or plates being heated, the shields being employed to protect 25 and prevent overheating of the longitudinal edges of the sheets and plates.

A pair of pinch rollers 24, 24, at least one of which is positively driven, are provided at the inlet end of the muffle which are arranged to be driven at variable speeds to suit the varying thicknesses and sizes of sheets and plates, these rollers being employed to feed the plates 19 into the furnace at the required speed. A similar pair of 30 positively actuated pinch rollers 25, 25, at the exit end of the muffle 2 affords means for feeding the heated sheets forwardly out of the furnace into the atmosphere.

In carrying out my improved method with 40 the apparatus which has been described, the gas burners 12 and 13 are first carefully regulated to uniformly heat the combustion chamber 2 and the interior of the muffle 6, and cold air is caused to pass through the 45 pipes 21 to maintain the sides of the muffle at the desired temperature. The sheets and plates, after being cleaned by pickling or cold rolling, or by both pickling and cold rolling, to remove all scale and provide the 50 materials with clean metallic surfaces, are moved singly by the pinch rollers 24, 24, into the inlet end of the muffle where each plate is allowed to remain until evenly heated throughout to a black-red color, a temperature 55 corresponding to between 750 degrees and 1000 degrees Fahrenheit. Upon becoming heated the sheet or plate is gradually moved through the muffle by the pinch rollers 25, the furnace preferably being of such 60 length as will enable the pinch rollers 25 to engage with the front end of the plate before the rear end is clear of the feed-in pinch rollers 24.

The front end of the individual sheet or

plate passes from the interior of the muffle 8 65 into the atmosphere, and as the successively different portions of the heated sheet or plate become exposed to the atmosphere the cooling effect of the air will oxidize the heated sheets and plates to a uniform blue color, 70 and the plates, (and successively exposed portions of the individual plates) being equally heated to the same temperature as they emerge from the muffle, variations in the color of the sheets or plates and of different portions of the surfaces of the individual sheets and plates will be avoided and 75 prevented.

The supply of air and gas to the series of 80 gas burners 12 and 13 is regulated and controlled to heat the muffle 8 to suit the size and gage of the sheets and plates being treated, and the volume of air supplied by or passed through the cooling tubes 21 within the furnace muffle is regulated from time 85 to time so as to heat the interior of the muffle equably. The operator, knowing the speed at which the plates can be fed into and through the furnace in order to become 90 equally heated, will cause the pinch rollers 24 and 25 to move the plates at the desired rate of speed.

The above described operations are then carried out on each individual sheet and plate, each sheet or plate being treated as a 95 separate unit.

The advantages of my invention will be appreciated by those skilled in the art. By heating the individual sheets and plates to a uniform temperature within a muffle and 100 progressively exposing the successively heated portions of the sheets and plates to the oxidizing influence of the atmosphere, each sheet and plate is blued to the desired uniform color, and the necessity of heating 105 the sheets and plates in packs and then removing and exposing the heated plates singly to the oxidizing atmosphere by removing the sheets and plates singly from the heated pack, is avoided and overcome. 110

Modifications in the construction and arrangement of the parts of the apparatus used in carrying out this invention may be made without departing from my invention as defined in the appended claims. 115

I claim:—

1. In the manufacture of blued sheets and plates the steps consisting in heating individual sheets or plates equably within a muffle furnace to a black-red color, then 120 withdrawing the uniformly heated sheet or plate from the muffle into the atmosphere, protecting the edges of the sheet or plate in heating and gradually exposing the heated sheet or plate to the action of the atmosphere in the withdrawal thereof to thereby fix the color of the blued sheet or plate. 125

2. In the manufacture of blued sheets and plates the steps consisting in heating individual sheets or plates equably within a muffle furnace to a black-red color, then withdrawing the equally heated sheet or plate from the muffle into the atmosphere, and gradually exposing the heated sheet or plate to the action of the atmosphere in the

withdrawal thereof to thereby fix the color of the blued sheet or plate.

10

In testimony whereof I have hereunto set my hand.

AMBROSE RIDD.
